FABRIC TREATING CABINET

Dudley P. Combs, Newton, Iowa, assignor to The Maytag
Company, Newton, Iowa, a corporation of Delaware

Application May 17, 1954, Serial No. 30,535

Term of patent 14 years

(Cl. 49—1)

FIG. 1

To all whom it may concern:

Be it known that I, Dudley P. Combs, a citizen of the United States, residing at Newton, county of Jasper, and State of Iowa, have invented a new, original, and ornamental Design for a Fabric Treating Cabinet, of which the following is a specification, reference being had to the accompanying drawings forming a part thereof.

Figure 1 is a perspective view of a fabric treating cabinet embodying my design.

Figure 2 is a view in front elevation of the fabric treating cabinet shown in Figure 1.

Figure 3 is a view in side elevation of the fabric treating cabinet shown in Figure 1.

Figure 4 is a vertical cross sectional view of the cabinet taken in the plane represented by line 4—4 of Figure 2.

The opposite side of the fabric treating cabinet not in view is similar in appearance to the side shown in Figure 3.

I claim:

The ornamental design for a fabric treating cabinet, substantially as shown and described.
